WO D202893-001 * 11/2019

Primary Examiner — Bridget L Eland

(74) Attorney, Agent, or Firm — James A. Sheridan; Sheridan Law, LLC

(57) **CLAIM**

I claim the ornamental design for a surgical spinal retractor, as shown and described.

DESCRIPTION

FIG. 1 is a perspective view of a surgical spinal retractor, showing my new design;

FIG. 2 is a right side elevational view of the surgical spinal retractor;

FIG. 3 is a left side elevational view of the surgical spinal retractor;

FIG. 4 is a top plan view of the surgical spinal retractor;

FIG. 5 is a bottom plan view of the surgical spinal retractor;

FIG. 6 is a rear elevational view of the surgical spinal retractor; and,

FIG. 7 is a front elevational view of the surgical spinal retractor.
